UNITED STATES PATENT OFFICE.

WARREN F. BECK, OF ELMIRA, NEW YORK.

MANIFOLD SALES-BOOK.

SPECIFICATION forming part of Letters Patent No. 732,257, dated June 30, 1903.

Application filed December 20, 1902. Serial No. 136,008. (No model.)

To all whom it may concern:

Be it known that I, WARREN F. BECK, a citizen of the United States, residing at Elmira, in the county of Chemung and State of New York, have invented certain new and useful Improvements in Manifold Sales-Books, of which the following is a specification.

My invention relates to improvements in manifold sales or order books wherein triplicate copies of the order or sales memoranda are to be made—that is to say, an original and two copies, the original to be sent to the cashier or bookkeeper, one copy to go to the customer with his purchase, and the third copy to be retained by the clerk or salesman; and the object of my improvements is to provide a simple and inexpensive arrangement of the pads required to make up such a book and also to so arrange said pads relatively to one another as to facilitate and convenience the manipulation of the book.

To this end my improved book comprises, primarily, two pads the one shorter than the other and superposed thereon, the two pads being held together by a binder or holder, with the back of the under pad or book projecting beyond the end of the upper pad, whereby the upper pad may be lifted to allow the leaves of the under pad to be dropped into place as they receive the memoranda, the blank leaves of this under pad being laid on top of the upper pad when the book is not in use.

I accomplish my object by means of the arrangement and assemblage of the several parts going to make up the book, as illustrated in the accompanying drawings, in which—

Figure 1 represents a perspective view of my improved book with the several leaves arranged in position for making a memorandum; Fig. 2, a side view of the same book with the leaves arranged in a different position; Fig. 3, a side view, also in perspective, of my book secured in a separable holder or cover; Fig. 4, a side elevation of the book shown in Fig. 3 detached from the holder and with the upper pad lifted away from the lower one, and Fig. 5 illustrates a modifica-

tion in which the pads are formed separately and attached to a special form of holder.

Like letters of reference designate like parts in the several views.

Referring first to Figs. 1 and 2, A represents a pad composed of original and duplicate leaves *a a'*, assembled in pairs, the originals being shorter than the duplicates and interfolded therewith and the duplicates being provided with stubs by which they are secured together by the usual form of stapling or stitching. These original and duplicate leaves are provided in the usual way with perforations between each original and duplicate and between the duplicate and its stub, whereby they may be readily separated from the pad and from one another. The stub of the pad A is also secured to a backing D, of rather heavy Manila or other paper, said backing being folded at E and brought back at F to a point beyond the stub of pad A, where it has attached to it a second pad B, made up of thin tissue or manifold paper, and the backing is then carried on beyond to form the cover G, which folds over the top of the pads when the book is closed. Fastened in at the top of pad A is a carbon or transfer sheet C, both faces of which are coated with the transfer medium. This carbon-sheet and also the tissue leaves are provided with thumb-holes at T for convenience in manipulating the book.

In use this book may be held in the left hand in the position shown in Fig. 1. As the book is opened the cover and tissue leaves *b*, which lie on top of the pad A, will be thrown back in the position shown in Fig. 2, thus exposing the transfer-sheet C and one corner of the underlying original leaf *a*. One of the tissue leaves *b* will then be laid upon the transfer-sheet C, after which the original leaf *a* will be brought up from under the transfer-sheet by grasping its corner, which is exposed through the thumb-holes T and laid down over the tissue sheet *b*, the several leaves being then in the position shown in Fig. 1, ready for receiving the memoranda. After receiving this memoranda the original and duplicate leaves *a a'* will be separated from the book by tearing them from the stub and the triplicate

leaf *b* will be dropped down beneath the pad *A* by lifting said pad and its backing *D*, as indicated in Fig. 4, after which the pad *A* will be again dropped into position upon the 5 top of the leaves *b*, which have received the memoranda, and the several leaves of the pad will again assume the position shown in Fig. 2, ready for repeating the operation when making the next sale. The original 10 and duplicate leaves *a a'* will be separated, the one being sent to the cashier or book-keeper and the other to accompany the goods received by the customer. In this way the clerk or salesman retains on the leaves *b* of 15 pad *B* a memoranda of all sales made by him, corresponding with that sent to the book-keeper and given to the customer, and when all of the leaves of the pads have been used the stub of the upper pad and its backing *D* 20 may be cut away at the fold *E* and the book, composed of the backs or covers *F* and *G* and the pad *B*, filed away for future reference.

If it is desired to use my book of pads in connection with a stiff-backed holder or cover, 25 I may cut off the Manila cover *G* and staple to the back of the backing *F* of pad *B* a tongue of the Manila paper *H*, (see Figs. 3 and 4,) adapted to receive the bail *I*, which is hinged at the bend of the upright portion *K* of the 30 holder *J*, which holder is composed of sheet metal covered, preferably, by leatherette or other suitable fabric. To the holder *J* is attached a cover *G* of similar material and adapted to fold over on top of the pads when 35 the book is not in use.

In Fig. 5 I have shown another modification, in which the pads *A* and *B* are formed separate and attached to a specially-arranged holder. In this modification each pad has 40 stapled to its back a tongue-piece *H* and the holder is composed of the three hinged members *D*, *F*, and *G*, these members being made of covered metal instead of pliable paper, as in Fig. 1, the members *D* and *F* being provided with the bent-up portions *K* and the 45 bails *I* hinged thereto, by which the pads are readily and securely attached to the holder, this fastening device having been already covered by me in former Letters Patent. 50 For use in connection with this holder the two pads *A* and *B* will be put up separately, pads *B* being made somewhat longer than the pads *A*, and when one set of pads is used up another may be readily inserted in the holder, 55 which may be thereby retained for indefinite use, the pads *B* being removed from the holder and filed away. Instead of my bail-fastener any other device for securing the pads to the holders may evidently be utilized. 60 Other ways of assembling the pads may be utilized than those herewith shown without departing from the spirit of my invention, and I do not wish to be understood as confining myself to the particular arrangement of 65 the pads as illustrated.

Having thus described my improvements, what I claim as my invention, and desire to secure by Letters Patent, is—

1. In a manifold sales-book, the combination of a pad of leaves for taking original and duplicate copies, a double-faced transfer-sheet applied thereto, a second pad or book of leaves for triplicate copies placed with its back projecting beyond one end of the first pad, and a binder, said binder being attached to the under side of the first pad, bent back at the other end of said pad beneath the pad and attached to the under side of the second pad or book, whereby the two pads are held together in position to have the leaves of the 80 latter laid both over and under the former. 70

2. In a manifold sales-book, the combination of a pad of leaves for taking original and duplicate copies, a double-faced transfer-sheet applied thereto, a second pad or book 85 of leaves for triplicate copies placed with its back projecting beyond one end of the first pad, and a binder, said binder being attached to the under side of the first pad, bent back at the other end of said pad beneath the pad, 90 attached to the under side of the second pad or book and continued on beyond to form a cover for the whole. 90

3. In a manifold sales-book, the combination of a pad of double leaves, one half of 95 which are provided with stubs bound together and the other half folded in between, a double-faced transfer-sheet attached thereto and adapted to lie between the folded leaves, a second pad or book of leaves for triplicate 100 copies placed with its back projecting beyond the stub end of the first pad, and a binder, said binder having the stub end of said pad attached to it at one end and extending thence underneath the pad to the opposite 105 end thereof, where it is bent back upon itself, extending thence back beyond the stub end of said first pad, where it has attached to it the back of the second pad or book. 105

4. In a manifold sales-book, the combination with a pad of leaves for taking original and duplicate copies and a second pad or book of leaves for triplicate copies, of a binder to hold the two together in operative position comprising one member, to one end 110 of which the stub end of the first pad is attached, and a second member attached to the first member with a flexible joint at the other end thereof, said second member being turned back beneath the first and having attached 115 to it the second pad or book with the back of said second pad projecting beyond the stub end of the first pad. 120

5. In a manifold sales-book, the combination with a pad of leaves for taking original 125 and duplicate copies and a second pad or book of leaves for triplicate copies, of a binder to hold the two together in operative position comprising three members, the first member being provided with means for re- 130

movably attaching the first of said pads thereto, the second member being attached to the first with a flexible joint and turned back beneath said first member, means on said second member for removably attaching the second pad or book thereto with its back projecting beyond the free end of the first member, and the third member being attached

to the end of the second member with a flexible joint to form a cover for the whole. 10

In testimony whereof I have affixed my signature in presence of two witnesses.

WARREN F. BECK.
